ATTEST.

UNITED STATES PATENT OFFICE.

CHOBÉY TAKETOSHI, OF SAN FRANCISCO, CALIFORNIA.

GAME.

Application filed November 21, 1921. Serial No. 516,540.

To all whom it may concern:

Be it known that I, CHOBÉY TAKETOSHI, a subject of the Emperor of Japan, residing at San Francisco, in the county of San Francisco and State of California, have invented new and useful Improvements in Games, of which the following is a specification.

The present invention relates to a novel game which requires skill in the playing thereof and will prove exceptionally amusing to the players.

The object of the invention is to provide simple, inexpensive game apparatus with which a number of different games may be played in a highly amusing and entertaining manner, the game board being so marked and arranged and the game pieces being so related to the game board, that a great deal of skill is required to successfully play the game.

The invention possesses other advantages and features some of which, with the foregoing will be set forth at length in the following description where I shall outline in full that form of the invention which I have selected for illustration in the drawings accompanying and forming a part of the present specification. In said drawings I have shown one form of the construction of my invention, but it is to be understood that I do not limit myself to such form since the invention as expressed in the claims may be embodied in a plurality of forms.

Referring to the drawings:

Fig. 1 represents a top plan view of the game board of my invention.

Fig. 2 is a top plan view of the board showing the game pieces in position thereon as when starting the game.

Fig. 3 is a top plan view showing the game board and pieces with the game pieces in typical condition during the playing of the game.

Fig. 4 represents a top plan view showing the game apparatus and relation of the game pieces thereto at the completion of the game.

Fig. 5 is a top plan view of one of the game pieces.

Fig. 6 is a plan view of the game piece shown in Fig. 5 but of the opposite side of said game piece.

The game of my invention as shown in the drawings, comprises a game board 1, preferably of rectilinear outline and pro-

vided with a border 2 in the customary manner. The surface of the board is divided into an even number of squares 3, there preferably being sixty-four of such squares, 60 provided by a series of lines designated 4 and 5 respectively, and extending at right angles to one another. The lines being printed or painted, or otherwise applied to the surface of the board. In order to dispose the game pieces in a proper position for playing the game, certain of the squares 3 are marked as shown in Fig. 1. Preferably fourteen of the squares are marked with like characters, for example, with the letter A, as shown at 6, on opposite sides of the board, and fourteen are marked with a different characterization, preferably with the letter B, on the other opposite sides of the board, there being circles 8 concentrically arranged upon each square so marked, to distinguish the squares from the game pieces, as will be later described. The marking of the squares 3 as described, is arranged so that at each corner of the board 80 there is provided a playing zone 9 comprising four unmarked squares, contiguous to one another, thus providing four playing zones. The four central squares are marked, two of them, A and B, as shown at 10 and 11, and this with the other squares likewise marked at the sides, provides in the center of the game board a playing zone 12 of rectangular outline, comprising twelve unmarked squares 3. In addition to this zone, 90 there is provided at each side of the game board a zone 13 comprising two unmarked squares 3. Each of the playing zones 9 and 13 is bordered on one side by an edge of the game board and on its other side by the squares marked with the letters A and B.

The game pieces are preferably in the form of flat disks 14 characterized by different markings on opposite sides so when the game pieces are turned over on the game board one side will have one significance and the other side another significance to the players. I may use various means of distinguishing opposite sides of the pieces, for example, may letter one side A and the opposite side B, or may use colors, as desired. In addition to the letters A and B, I prefer to have like numbers, as shown at 15 on opposite sides of each game piece. I may also provide different characterizations 16 as shown in Figs. 5 and 6. The numbers may be arranged as desired, with relation to

the game pieces. They may be numbered from one to sixty-four (the actual number of game pieces) or numbered from one to sixteen, in groups of four, or in any other 5 way numbered in groups, as desired. As shown, the pieces are numbered in groups of four from one to sixteen, there being four marked one, four marked two, four marked three and so on to sixteen. The 10 characterizations 16 are different on opposed faces of each piece and preferably represent clubs, hearts, diamonds and spades, as used in playing cards. For example, on the A side of the game piece the number five 15 and a spade will appear, whereas on the opposite side of the same game piece the letter B, number five and a club will appear. The valuation of these characterizations 16 to the count of the game may be, as desired, 20 for example, diamonds may take the highest count, hearts next, clubs next, with the low count indicated by the spades, or any other arrangement may be provided, if desired.

25 The game is best adapted for two players and to start, the players place game pieces over the squares 3 marked by the characterizations A and B. The player A should place game pieces with the A side showing, 30 upon the A squares on certain opposite sides of the game board and then two A pieces upon the squares 10, in the center of the game board. The other player will place the B game pieces in the same manner, 35 until the board with the pieces thereon appears as shown in Fig. 2, and the game apparatus is ready to be used in the playing of the game. Any suitable method of determining which player is to make the first 40 move may be resorted to. This may be done by tossing a coin, cutting a deck of cards, or by having one of the several chips of the game bear a designation indicating "first play." By dividing 45 the pieces at the start of the game the man getting the "first play" game piece, will be entitled to the first move. Assuming that the first player is an A man, by placing a game piece in any of the squares marked 50 17, 18, 19, 20, 21, 22 and 23, as shown in Fig. 3, the A man may capture a B man. Thus at the start of the game the A man 55 may place a game piece upon any one of the three squares 17, 18 and 19, within the zone 12, or upon any of the squares 20 to 23 within two of the zones 13. Assuming that a game piece has been played upon the square 19 then the game piece B between the game pieces A, one of which latter is on 60 the square 19 and the other on the square 10, is captured and is turned over or reversed by the player A so that the A side of said B game piece is exposed. The object of the play is to place the game pieces so 65 that the opponent's game pieces lie between

the player's pieces, so that said opponents pieces may be captured and turned over. After A has played, as hereinbefore described, the B player has the same number of openings to capture an A man, and places 70 the game pieces upon the playing zone 12 or zones 13, so that an A man is captured. This play is continued until one or the other has captured all of the men or until no move is possible. In some instances the game may 75 be brought to a finish, with the pieces arranged as shown in Fig. 4, wherein there will be thirty-five A men showing to twenty-nine B pieces. Thus the A player would win 80 the game, having six more men than the B player. Another way to determine the count is by considering the numbers showing on the various game pieces. For example, if the A pieces, though six more than B pieces have smaller numbers showing than on the 85 B pieces, the B side would be the winner. Likewise the characterizations 16, that is, the hearts, diamonds, spades and clubs, may be utilized in determining the winner of the game. The diamonds representing the highest 90 count, hearts next, spades next and clubs the lowest.

In the playing of the game the fourteen game pieces of each player as originally placed upon the board are not moved from 95 their respective squares. They may be reversed or turned over however, during the play. Thus the players must effect a play by placing other game pieces upon any one of the unoccupied squares of the various 100 zones, provided, in placing such pieces "a capture" is effected, that is, so that one or more A pieces will be disposed between the two B pieces or vice versa. Since it is possible for either player to use any unoccupied square of the playing zones it is 105 desirable to place a game piece at the outward corner square of each zone 9. For example, if an A piece were placed in one of said corner squares and there were a 110 series of B game pieces in the squares leading outward in all directions from the said corner square with A pieces at the ends of said rows of B pieces, then all of the B pieces of each row interposed between said 115 A pieces would be captured and turned over so as to show the A sides thereof.

As shown in Fig. 3 the game pieces are arranged as when the game is in progress several plays having been made. For the 120 purpose of understanding the play, the pieces which have figured in the play will be given separate designations. Assuming that an A man has first play, he places the game piece 30 as shown in the drawing, and in so doing provides two A pieces the other being the piece 31 on opposite sides of the B piece 32. The B piece is captured and then turned over so that an A side will show. The B player then places the B piece 130

33 as shown, and thereby with the piece 34 captures the A piece 35 and immediately turns said A piece over to present a B side thereof. The next play is made by an A 5 man who places the game piece 36 so as to capture the piece 35, with the aid of the A piece 31, said piece 35 being at that time disposed with its B side uppermost, as a result of the second move of the play. The 10 B player then places a B game piece 37 as shown and thereby traps between said piece 37 and the B piece 38 the A pieces 30 and 35, which are turned to show the B side. The A player then follows by placing an 15 A piece 39 as shown, so as to trap and capture between it and the piece 36, the two, then B pieces numbered 30 and 33, this play is continued until the unoccupied spaces are filled and assume the appearance 20 shown in Fig. 4. With the game brought to a finish as shown in Fig. 4, there are thirty-five A pieces and twenty-nine B pieces, which would ordinarily prove the A side the winner. However, it will be noted 25 from the drawings that the larger numbers all appear upon the B chips and according to a count taken, by adding the numbers on the B chips, the B side would be the winner, though having less men showing.

30 I claim:

1. In a game, a board comprising a playing surface divided into sixty-four squares of which twenty-eight of the squares are marked with different designations, there 35 being six of the squares marked with like designations on certain opposite sides of the board and six with the other designations on the other two opposite sides, and other of the marked squares disposed in the center 40 of the game board of said marked squares, being so arranged with relation to one another that playing zones of four unmarked squares are provided at the four corners of the board, playing zones comprising two 45 squares are provided on the borders of the board between the corners, an additional playing zone consisting of twelve squares is provided around the center squares of the board between said squares and those on the 50 sides of the board, game pieces having differing characterizations on opposite sides thereof adapted to be mounted upon said marked squares and other similar game pieces to be placed upon the unmarked 55 squares around the first named pieces.

2. In a game, a board comprising a playing surface divided into sixty-four squares of which twenty-eight of the squares are marked with different designations, there 60 being six of the squares marked with like designations on certain opposite sides of the board and six with the other designations on the other two opposite sides, and other

of the marked squares disposed in the center of the game board of said marked squares, 65 being so arranged with relation to one another that playing zones of four unmarked squares are provided at the four corners of the board, playing zones comprising two squares are provided on the borders of the 70 board between the corners, an additional playing zone consisting of twelve squares is provided around the center squares of the board between said squares and those on the sides of the board, game pieces having differing characterizations on opposite sides thereof adapted to be mounted upon said marked squares and other similar game pieces to be placed upon the unmarked 75 squares around the first named pieces, said 80 game pieces having like numerals on opposite sides.

3. A game board comprising a playing surface divided into sixty-four squares of which six squares on each of certain opposite sides of the board are marked with like 85 designations, six squares on each of the other opposite sides of the board are marked with like designations differing from those upon the first named sides, the four central squares are marked, each two of them alike and corresponding to the designations on the said opposite sides, a plurality of game pieces equal in number to the squares on the playing surface and having, each of 90 them, like designations on certain sides and like designations on the opposite sides different from the designations on the first named sides, certain of said game pieces being placed upon the marked squares of the 95 surface, the remainder of the game pieces being adapted to be placed upon the unmarked squares.

4. A game board comprising a playing surface divided into sixty-four squares and 100 having twenty-eight of said squares marked, six of them on each of certain opposite sides alike, six of them on each of the other opposite sides of the board alike but of different 105 characterization than the marks on the first named sides and four of said squares marked in the center of the playing surface, said twenty-eight marked squares being so arranged as to provide playing zones at the corners of the board consisting, each of 110 them, of four unmarked squares, a playing zone around the center squares, playing zones at the sides between the corner zones and a plurality of game pieces, certain of 115 which are to be placed upon the marked squares and are not subject to being moved off of said squares during the playing of the game and the other of said game pieces being adapted to be placed upon the unmarked squares in the different playing zones.

CHOBEY TAKETOSHI.
